UNITED STATES PATENT OFFICE.

FREDERIC K. PLYMPTON, OF WELLESLEY, MASSACHUSETTS.

CLOSURE FOR MILK-JARS AND THE LIKE.

No. 886,014.

Specification of Letters Patent.

Patented April 28, 1908.

Application filed November 21, 1907. Serial No. 403,152.

To all whom it may concern:

Be it known that I, FREDERIC K. PLYMPTON, a citizen of the United States, residing at Wellesley, in the county of Norfolk, State 5 of Massachusetts, have invented a certain new and useful Improvement in Closures for Milk-Jars and the Like, of which the following is a specification, reference being had therein to the accompanying drawings.

10 The invention has relation to the disk-shaped so-called caps, covers, or closures which are used for sealing milk and cream bottles or jars and the like.

15 More particularly, the invention has relation to attachments for such caps, covers, or closures, of the class contrived for the purpose of facilitating the extraction of the latter from their seats within the mouths or necks of the bottles or jars to which they have been

20 applied.

Various forms of extractors have been proposed heretofore. Certain of these are made of metal strips, each attached by one end to the disk constituting a cap, cover, or closure, 25 with a handle portion or tab lying against the upper surface of the disk. The attachment of the extractor to the disk has been effected either by passing one end of the metal strip through the thickness of the disk 30 one or more times and clenching such end, or by means of a staple that is passed through the strip and the thickness of the disk and then clenched. In these instances the strip is made fast by one end to the disk at a point 35 inside the edge or periphery of the latter, and the handle-portion or tab extends inward toward the center of the disk. The extractor attachment thus applied is utilized in effecting the removal of the cap or cover from the 40 mouth of a bottle or jar, by lifting the free end of the handle portion or tab from the upper surface of the cap or cover, and then pulling upward upon the same until the marginal portion of the cap or cover at one side 45 and adjacent the point of attachment of the extractor has been started at such side, the complete removal of the cap or cover being thereby facilitated.

The invention is designed as an improvement in extractor attachments of the class 50 just described. In the case of the attachments with which I have become acquainted, the attachment itself is secured to the disk of the cap or cover at more or less distance from the edge of such disk. When a cap or cover with extractor attachment thus applied is in

place within the seat at the mouth of a bottle or jar, and an upward pull is exerted through the handle or tab of the extractor, such pull, taking effect primarily at the point of connection with the disk, that is to say at a greater or less distance from the edge of the disk, acts at the same distance from the place where such edge is in engagement with the confining portion of the bottle. Therefore, 60 not only is the lifting pull distributed around a greater or less portion of the margin of the disk, but the tendency of such pull to lift the disk continues to be resisted at the edge itself by the engagement of such edge with the confining portion of the bottle. Hence, a considerable degree of resistance at the nearest portion of the edge of the disk, opposing withdrawal, has to be overcome by the pull which is applied within the inclosure of the edge or 65 periphery, before the edge can be started. 70 When the cap or cover is started, it is apt to come too suddenly.

One of the objects of my invention is to provide an extractor attachment which shall 80 be so applied to the edge of the disk of a cap or cover that the pull exerted for the purpose of effecting the removal of the cap or cover from the mouth of a bottle or jar shall take effect upon the exterior of the said edge, 85 itself, and shall act directly against the said exterior with a tendency to draw first that portion of the edge to which the attachment is applied away from the confining portion of the bottle, and to then gradually strip or 90 withdraw from the seat the remaining portions of the edge at opposite sides of the place of attachment of the extractor. Thereby the pulling strain will be concentrated primarily at the point of application of the 95 attachment, instead of being distributed around a greater or less extent of the edge or periphery of the disk, and by acting with a tendency to pull the edge out from the confining portion of the bottle at such point first 100 will render the removal of the cap or cover much easier to effect than heretofore. At the same time, the withdrawal will take place more gradually.

The invention further has as one of the objects thereof to enable the extractor to be attached to the disk of the cap or cover without passing it through the thickness of the said disk, and without the use of staples, so as thereby to avoid certain defects and drawbacks of some of the extractors heretofore proposed. That is to say, when the extrac- 105

tor is attached to a cap or cover by inserting one end thereof through the material of the disk, and clenching such end at the under side of the disk, the said end may partly straighten 5 under a pull, and draw out of the slit, or the clenched end may tear loose, especially if the lifting force is suddenly exerted. When a staple is used it likewise is liable to become unclenched or to tear loose. The said object 10 of the invention is to enable the extractor to be attached in a manner which will obviate any such liabilities.

The invention consists in an extractor attachment which is fitted around the edge of 15 the disk of a cap or cover, with one portion or limb thereof in contact with the under surface of the said disk, and with the other portion or limb thereof in contact with the upper surface of the disk and extended toward 20 the center of the disk to constitute a handle or tab. When a cap or cover equipped with such an attachment is fitted to its seat in the mouth or neck of a bottle or jar, the outermost portion of the attachment fits into 25 place in connection with such seat without interfering with the tightness of the sealing. When the inner end of the handle or tab is lifted and pulled upward, it draws that portion of the edge of the disk which is clasped 30 by the attachment upward out of the seat, without the tendency to tear loose that exists in the cases previously mentioned.

Embodiments of the invention are represented in the drawings.

35 In the latter,—Figure 1 shows in plan the neck or mouth of a bottle sealed by a cap or cover having one embodiment of the invention applied thereto. Fig. 2 is a view in section on line 2, 2, of Fig. 1. Fig. 3 is a bottom view of the cap or cover of Figs. 1 and 2, with its extractor attachment. Fig. 4 is a 40 perspective of the extractor attachment of Figs. 1, 2 and 3, in a partially bent state, detached, and on an enlarged scale. Fig. 5 is 45 a bottom view of a cap or cover having a second embodiment of the invention applied thereto. Fig. 6 is a view in section on line 6, 6, of Fig. 5. Fig. 7 is a top view showing a third embodiment of the invention. Fig. 8 50 is a view in section on line 8, 8, of Fig. 7.

Having reference to the drawings,—at 1, Figs. 1 and 2, is the mouth portion of a milk-jar. These figures show a cap or cover 2 applied to the seat which is formed within the 55 said portion, as usual in sealing the mouth or neck of a milk-jar.

At 3 is an extractor attachment applied to the said cap or cover and embodying the invention. As previously described herein, 60 the said extractor consists of a strip of metal which is fitted around the edge of the disk constituting the cap or cover, with one limb thereof resting in contact with the under surface of the disk, and the other limb resting in 65 contact with the upper surface of the latter.

The upper limb preferably is somewhat longer than the under one, to give it greater flexibility, and constitutes the handle or tab. The under limb is comparatively short, because flexibility thereof is not required. The 70 closed bend of the strip where the latter fits the edge of the disk does not materially break the uniformity of the edge of the cap or cover, and when the cap or cover with its extractor attachment embodying my invention is inserted into the seat of the mouth or neck of a bottle or jar the said bend fits in place in such seat without interfering with the perfect sealing of the bottle or jar. Normally, the handle or tab lies close to the 80 upper surface of the disk, but when it is desired to extract the cap or cover the handle or tab is lifted so that it assumes a position like that shown in dotted lines in Fig. 2. Thereupon, a pull upward and toward the 85 right in such figure will start the side of the disk with which the extractor is engaged, drawing such side from its seat and clear of the rim above the latter, rendering it easy to complete the removal of the cap or cover. 90 At the time of being applied to the disk, the bent strip is pinched tightly upon the latter.

To prevent accidental dislodgment of the extractor from the disk at any time prior to the insertion of the cap or cover into the 95 mouth or neck of a bottle or jar, I contemplate in some cases bending up spurs 3^a, 3^a, at the free end of the under limb to enter the material of the disk. Fig. 4 shows the said spurs bent up in readiness to be entered into 100 such material, and Fig. 3 shows them thus entered, looking at the under side of the cap or cover. In Figs. 5 and 6 a hole 3^b has been made in the lower limb, producing a bur which is shown as entered into the material 105 of the disk, thereby engaging such limb with the disk. Figs. 7 and 8 show the extractor corrugated, as by the effect of pressure between corrugated surfaces after the application of the device to the disk, thereby increasing the hold of the device upon the disk. These different methods of effecting engagement of the extractor with the disk have the advantage that they safeguard against the 110 lower limb drawing away from the disk at 115 the time when the handle is lifted and pulled upward as described hereinabove.

The rounded free end of the handle or tab of the extractor, shown in Figs. 1, 4 and 7, is advantageous, because it has no tendency to 120 cut or cause injury when a person inserts the edge of his finger-nail beneath the same in picking it up, preliminary to bending the handle upward as in Fig. 2. In forming the successive extractors from a continuous strip 125 by cutting the latter transversely into short lengths, the operation of cutting out this rounded end will leave the opposing end of the next extractor concave, as in Fig. 5. The opposite horns of the concavity simply 130

have to be turned up at an angle to the plane of such end, as in Fig. 4, to form the spurs 3^a, 3^b.

What is claimed as the invention is:—

5 1. A bottle or jar closure or cover comprising a thin disk and an extractor fitting around the edge of the said disk clasping the latter, with a handle or tab at the upper surface of the disk which normally lies close to 10 said surface and is adapted to be lifted therefrom.

15 2. A bottle or jar closure or cover comprising a thin disk and an extractor fitting around the edge of the said disk and clasping the latter, with a flexible handle or tab at the upper surface of the disk and a second limb

at the under surface thereof engaged with the material of the disk.

3. A bottle or jar closure or cover comprising a thin disk and an extractor fitting 20 around the edge of the said disk and clasping the latter, with a flexible handle or tab at the upper surface of the disk and a second limb at the under surface thereof having a projecting portion engaged with the material of 25 the disk.

In testimony whereof I affix my signature in presence of two witnesses.

FREDERIC K. PLYMPTON.
